US00D868098S

(12) United States Design Patent (10) Patent No.: US D868,098 S
Suslik et al. (45) Date of Patent: * Nov. 26, 2019

(54) DISPLAY SCREEN OR PORTION THEREOF WITH GRAPHICAL USER INTERFACE

(71) Applicant: Aristocrat Technologies Australia Pty Limited, North Ryde, NSW (AU)

(72) Inventors: Igor Suslik, St. Ives (AU); Christian Salmon, Manly (AU); Jason Meyer, Wyoming (AU)

(73) Assignee: ARISTOCRAT TECHNOLOGIES AUSTRALIA PTY LIMITED (AU)

() Term: 15 Years

(21) Appl. No.: 29/685,510

(22) Filed: Mar. 28, 2019

Related U.S. Application Data

(63) Continuation of application No. 29/673,333, filed on Dec. 13, 2018, now Pat. No. Des. 847,189, which is a continuation of application No. 29/616,091, filed on Sep. 1, 2017, now Pat. No. Des. 839,899.

(57) CLAIM

The ornamental design for a display screen or portion thereof with graphical user interface, as shown and described.

DESCRIPTION

The FIGURE is a front view of a display screen or portion thereof with graphical user interface, showing our new design.

The outer perimeter shown in dashed broken lines in the drawings illustrates a display screen or portion thereof that forms no part of the claimed design. The remaining dashed broken lines in the drawings illustrate portions of the graphical user interface that form no part of the claimed design.
